Attorney

UNITED STATES PATENT OFFICE.

WILLIAM JOHN BOUSQUET, OF SPRINGFIELD, MASSACHUSETTS.

GUIDE AND HOLDER FOR FLEXIBLE RULES.

1,312,887.

Specification of Letters Patent. Patented Aug. 12, 1919.

Application filed June 29, 1917. Serial No. 177,837.

To all whom it may concern:

Be it known that I, WILLIAM J. BOUSQUET, a citizen of the United States of America, and a resident of Springfield, in the county of Hampden and State of Massachusetts, have invented certain new and useful Improvements in Guides and Holders for Flexible Rules, of which the following is a full, clear, and exact description.

- 10 This invention relates to improvements in rule guides and holders, and is especially designed to provide a simple device which may be quickly positioned on a thin flexible rule, such as are commonly used by machinists, 15 tool makers, testers, and others, and which can be used as a guide for taking measurements with the rule, or can be used to hold the rule in a pocket of a vest, coat or other garment.
- 20 The invention is embodied in a one piece device which is formed with two parallel in-turned flanges adapted to embrace the opposing edge portions of a thin flexible rule, and with a spring tongue formed of the material 25 between the flanges and functioning to hold the guide on the rule against accidental movement or too free movement and also to hold the rule on the pocket of the garment of the user of the device.
- 30 With the above and other objects in view the invention consists in certain new and useful combinations, constructions, and arrangements of parts, clearly described in the following specification and fully illustrated in the accompanying drawings, in which:—

Figure 1 is a plan view showing my improved device applied to a thin flexible rule, the drawing being full size.

- 40 Fig. 2 is a bottom plan view thereof, in full size.

Fig. 3 is an end view showing the relation of the ball of the spring tongue to the flanges, whereby the movement of the spring tongue toward the flanges is limited, so that the flexible rule may be inserted between the flanges and the tongue, without becoming wedged between the tongue and the main body portion of the device, taken on an enlarged scale.

Fig. 4 is a view in cross section showing a slightly modified form of the device, taken on an enlarged scale.

Fig. 5 is a simple view showing another modified form of the device.

Fig. 6 is a plan view of a device equipped with a ball tongue terminal.

Referring to the accompanying drawings illustrating the practical embodiment of my invention 5 designates the central or main body portion of the device, which has a tapered spring tongue 6 stamped from the material thereof. This tongue is bowed at 6^a so as to provide spring tension on the free end 6^b thereof, which is formed with dished or ball points 6^c, adapted to permit of easy engagement with the garment or with the rule. The device is provided on the forward end thereof with an extension 5^a which projects beyond the flanges 7 and 8 formed on the sides of the device and inturned against the underside of the main body or central portion 5, and slightly spaced therefrom to admit the flexible rule between said flanges and said main body portion. The flanges 7 and 8 are also formed with rounded corner portions 9, whereby a relatively wide space is provided on the opposite end of the device, to permit of the easy insertion of the rule between the flanges and the main body portion, as will be readily understood.

As shown in Fig. 3 the opposing edge portions of the flanges 7 and 8 project under the ball point or dished terminal of the spring tongue, thereby preventing further movement of said ball point or dished terminal toward said flanges. The tip of said ball point or dished terminal projects slightly above the surface of the main body portion 90 or central wall 5 so that it will be normally spaced from the adjacent face of said wall, whereby a garment may be wedged between the tongue and the wall, and the device, together with the rule inserted therein, 95 clamped on the pocket of the garment of the user, and thereby prevent loss of the rule.

The flanges may be formed with longitudinally inset portions 7' and 8', whereby increased frictional engagement of said flanges with the rule will result, as shown in Fig. 4, or the device may be formed with spring coils 10 and 11 connecting said flanges to the main or central wall or portion 5, so that the flanges will exert spring 105 tension on the rule.

The device is formed in one piece and when applied to a rule will not render said rule clumsy or impair the use thereof. When the device is applied to a rule the end 110

a may be placed against the work to be measured and the rule shifted to get the proper measurement.

In Fig. 6 I show a device in which the 5 spring tongue is provided with a ball terminal 6^a, for engagement with the garment.

By applying pressure by the thumb upon the spring tongue the frictional engagement 10 of the device on the rule may be increased at will, so as to hold the device in fixed indicating position.

Having described my invention I claim and desire to secure by Letters Patent:—

A combined rule guide and holder consisting of a one-piece device having a central wall and parallel inset flanges slightly spaced from said wall to slidably retain a

thin flat rule therebetween, said flanges having longitudinal corrugated ribs for engagement with the rule and said central wall 20 having a spring tongue formed thereon, said spring tongue having a dished terminal portion movable between the opposing edges of the flanges but wider than the space between said flanges, whereby the flanges will prevent a wedging action of the tongue therebetween and a rule can be inserted between said tongue and said flanges without becoming wedged between the tongue and the central wall.

Signed by me at Springfield, Massachusetts.

WILLIAM JOHN BOUSQUET.
